UNITED STATES PATENT OFFICE.

WILLIAM ZACHOW, OF RACINE, WISCONSIN.

STRAW-STACKER.

1,186,505.

Specification of Letters Patent.

Patented June 6, 1916.

Application filed October 11, 1909. Serial No. 521,995.

To all whom it may concern:

Be it known that I, WILLIAM ZACHOW, a citizen of the United States, and a resident of Racine, county of Racine, and State of 5 Wisconsin, have invented certain new and useful Improvements in Straw-Stackers, of which the following is a specification.

The invention relates to stacking mechanism which receives the straw and chaff 10 from threshing machines and which are arranged to deliver it to form a stack.

The invention seeks to provide a simple, effective, compact construction which can be readily mounted upon the rear end of the 15 threshing machine and in which the delivery end can be swung back and forth to form the stack or swung over the threshing machine out of the way.

The invention also seeks to provide improved means whereby the straw is forced 20 through a closed channel or conduit by the use of packing devices, so that the necessity of employing a blast fan or endless raddle mechanism is avoided.

In the preferred form of the invention 25 illustrated, the chaff is delivered to the straw by a fan and the delivery section of the stacker is provided with a raddle but these parts can be otherwise arranged without departure from the broad spirit of the invention.

A further object of the invention is to so arrange the straw-carrying or forcing means 30 that it is not necessary to drop the straw down from the end of the racks of the threshing machine and thereafter elevated again as in the ordinary stacker construction.

In the preferred form, the invention further 35 seeks to provide separate means for delivering the straw and chaff from the racks and sieves of the threshing machine to the delivery section of the conveyer and to otherwise improve and simplify the operating 40 parts.

With these objects in view, the invention 45 consists in the features of improvement hereinafter set forth, illustrated in the preferred form in the accompanying drawings and

more particularly pointed out in the appended claims.

In the drawings, which illustrate the preferred form of the invention, Figure 1 is a view in elevation of the rear end of a threshing machine with the improved stacker attached thereto. Fig. 2 is a detail view in elevation of its mechanism for swinging the delivery end of the stacker and for reversing the directions of movement. Fig. 3 is a section on the line 3—3 of Fig. 2. Fig. 4 is a section on the line 4—4 of Fig. 2. Fig. 5 is a longitudinal, central section of the improved stacker. Fig. 6 is a detail plan view of the conveyer and fan for the chaff, the section being taken on the lines 6—6 of Figs. 65 1 and 5. Fig. 7 is a detail view on an enlarged scale with parts shown in section on the lines 7—7 of Figs. 1 and 5. Fig. 8 is a plan view of the stacker and the operating mechanism for the delivery section thereof 70 and with parts shown in section on the lines 8—8 of Figs. 1 and 5.

The drawings illustrate the rear end portion of the thresher to which the stacking mechanism is attached. The rear ends of 75 the sills 10 of the stacker are illustrated from which rise the angle-bar uprights 11. The casing of the thresher comprises, as usual, a roof 12 and side-walls 13. The rear ends of the straw rack 14 and sieves 15 of the 80 stacker, are illustrated. The straw rack separates the grain from the straw and delivers the straw at the rear end of the threshing machine and the sieves 15 separate the chaff from the grain and deliver the chaff 85 out at the rear end of the thresher, the chaff being usually separated from the grain by a fan which blows through the sieves 15.

The frame of the stacker is formed preferably of angle-bars and comprises the front 90 and rear bars 16 and 17 which are attached at their upper ends to the corners of a rectangular frame 18 which is also formed of angle-bars. The front uprights 16 of the stacker frame are vertical and are detachably bolted to the uprights 11 of the threshing machine. The rear upright bars 17 are inclined inwardly at their lower ends to-

ward the front angle-bars 16 and are connected thereto, at their lower ends, on one side by the fan casing 19 and on the opposite side by a casting 20. Inclined, bracing side-bars 21 connect the upper, rear portion of the horizontal frame 18 and the front upright bars 16. The inclined brace-bars 21 are connected intermediate their ends by a transverse angle-bar 22 and the ends of this bar are connected to the rear uprights 17 by short angle-bars 23. The stacker is provided with side walls 24 and a rear wall 25, preferably of sheet metal, but the front is open to communicate with the rear, open end of the threshing machine. The lower edge of the rear wall 25 is curved forwardly and upwardly to form a hopper 26 beneath the rear end of the sieves and which collects the chaff coming therefrom. The upper, forward edge of the hopper 26 is connected, as shown, to a cross-bar 27. The stacker casing is divided between its upper and lower ends by an inclined plate or wall 28 that is secured to the inclined bracing angle-bars 21. Above the partition plate 28 are arranged a pair of inclined, inwardly-curved walls 29 which extend inwardly from the side walls 24 of the stacker casing over the partition plate 28. A portion of the wall 29 is formed of a series of curved strips 29^a which are spaced apart to form a series of slots through which the feeding or packing devices extend, as hereinafter described. The walls 29, strips 29^a and the plate 28 form a funnel like construction into which the straw is delivered from the threshing machine by the straw racks 14 thereof. The straw thus delivered onto the plate 28 and into position between the plate 28 and curved strips 29^a is picked up by the feeding or packing devices and forced between the strips and through a closed conduit section or throat 30. The throat 30 extends upwardly from the funnel or straw receiving hopper formed by the plates 28 and 29. The throat is preferably formed of two sections of cast metal which are secured together and supported at their upper ends from a circular casting 31. The circular casting is mounted at the upper, horizontal portion of the stacker frame upon a transverse angle-bar 32 which extends between the side-bars of the top frame 18 and upon a pair of bars 33 which extend between the cross-bar 32 and the rear bar of the frame 18.

The circular casting 31 is formed of upper and lower sections bolted together and which are provided with a raceway for a row of balls 34. These balls support a rotatable conduit or pipe section 35 and engage a raceway formed in the lower end thereof. The conduit section 35 is preferably in the form of a short cylindrical casting formed of two sections bolted to-

gether. The upper section is provided with a horizontally projecting circular flange 36 and an upwardly-extending rectangular flange 37. An extension or curved hood 38 is mounted upon the casting 35 and is secured to the rectangular flange 37 thereof.

When the stacker is mounted in position upon the threshing machine, the straw racks of the latter extend within the hopper or funnel formed by the plates 28 and 29 and the straw is delivered from the racks onto the plate 28 and between the plates 29, and is forced through a closed conduit or channel formed by the stationary throat section 30 and a rotatable chute section comprising the cylindrical casting 35 and the hood or extension 38, by means of a series of packing devices or feeders which operate through the slots between the strip pieces 29^a. These strip pieces are secured at their outer ends to the side walls 24 of the stacker casing and to inclined bracing angle-bars 39 which extend between the angle-bars 21 and the upper ends of the upright angle-bars 16. The upper, inner ends of the strip pieces 29^a are secured to lugs 40 upon the lower edge of the throat 30. There are two packing devices or feeders on each side of the opening or throat 30, as shown in Fig. 7. Each packing device or feeder comprises an arm 41 having a segment-shaped end or head 42, to the opposite edges of which two rows of teeth 43 are secured. A pair of inclined crank-shafts 44 are arranged outside of the walls 29 of the hopper or funnel and inside the side walls 24 of the stacker casing. These axes of these shafts are inclined and substantially parallel to the inclined walls 29. At their lower ends, the crank-shafts 44 are mounted in bearings 45 fixed to the cross angle-bar 22. At their upper ends, the shafts are journaled in bearings 46 fixed to the transverse angle-bar 32. Each shaft 44 is provided with two crank portions 47 diametrically opposite each other and the stacker or feeder arms 41 are provided with bearings 48 bolted thereto and engaging the crank portions 47 of the shaft. Individual links 49 are pivoted to the outer ends of the arms 41 and to brackets 50 fixed to the side walls 24 of the stacker casing. A transverse drive shaft 51 extends through the stacker casing and is journaled at its ends in boxes 52 fixed to the short angle-bars 23. This shaft is provided with a pair of oppositely arranged beveled pinions 53 which engage beveled gears 54 on the rear lower ends of the crank-shafts 44. This drive mechanism rotates the shafts 44 in opposite directions, as indicated by the arrows in Fig. 7, and thereby imparts a combined rotary and reciprocating motion to the packer arms 41, so that the teeth 43 on the packers are projected through the outer ends of the slots

between the strips 29, are moved upwardly to force the straw in the hopper or funnel through the adjacent portions of the strips 29 and through the throat 30 and the rotatable chute section formed of the parts 35 and 38. At the ends of the movement of the packers toward the throat they are withdrawn from the slots between the strips 29 and thereby automatically clear themselves 10 of the straw. By this means, the straw delivered from the ends of the straw racks 14 of the threshing machine is forced through the stationary and rotatable sections of the closed conduit or channel and the straw is 15 pushed up directly from the end of the straw rack without first dropping down therefrom, as in prior stacker constructions. A fan casing 19 is arranged at one side 20 of the stacker casing and at the end of the chaff hopper 26 in the lower portion thereof. A transverse shaft 56 extends through the hopper 26 and the fan casing 19 and is journaled at one end in a bearing formed in the casting 20 and at its other end in a bearing 25 57 on the fan casing. This shaft is provided with a spiral series of L-shaped blades 58 which are inclined in position to form a broken auger or screw and which serves to feed the chaff collected in the hopper laterally into the fan casing 19. A vertical conduit or pipe 59 extends upwardly from the fan casing and at its upper end is provided with a laterally extending horizontal portion 60 having a downturned end or 30 elbow 61. The elbow 61 opens into the upper portion of the hood 38 in line with the axis of the rotatable chute section. The elbow is preferably provided with an angle-bar flange 62 which engages the hood 38. 35 The fan casing 19 is provided with a suitable series of fan blades 63 mounted on the shaft 56 which serves to force the shaft in the casing through the pipe or conduit 59 and through the horizontal portion 60 and elbow 61 into the hood 38 and into the straw therein.

The transverse drive-shaft 51 for the packers and the transverse shaft 56 in the chaff hopper are provided on one end with 50 a pulley, the pulley 64 on the shaft 51 being larger than the pulley 65 on the shaft 56. A drive belt 66 extends from the forward part of the threshing machine over the pulleys 64 and 65 and around a tightener pulley 67. This tightener pulley is mounted upon the end of an arm or lever 68 which is pivoted upon the casting 20, and the lever may be shifted to tighten the belt 66. The dog 69 on the lever is arranged to engage a 60 notched segment 70 formed on the casting 28 to lock the lever in position.

The ordinary pneumatic straw stacker is objectionable in that the straw and chaff are delivered therefrom with such force by

the air blast that it is impossible for men to 65 remain on the stack to properly form the same. The ordinary mechanical stacker is objectionable because it is heavy and clumsy and does not compactly deliver the straw. In the present improved construction, the 70 greater amount of work is mechanically effected and only a very small fan and air blast are employed for elevating the chaff, so that the objections to the pneumatic stacker are obviated. The packers force the 75 straw through a closed conduit or channel and compress the straw so that the delivery chute section can be small and compact, as with the ordinary pneumatic stacker. Moreover, the delivery chute section in the applicant's construction is at the upper portion 80 of the machine out of the way and can be rotated back and forth to distribute the straw or swung over the top of the threshing machine when not in use. The improved 85 construction therefore possesses all the advantages of the mechanical stacker and at the same time is small, compact, and can be as readily handled as the ordinary pneumatic stacker. 90

As the operation of the stacker is largely mechanical, it is necessary to relieve the force of the air-blast which is projected by the fans of the threshing machine out through its rear end. For this purpose, the 95 triangular portions of the side walls of the stacker casing between the inclined brace-bars 21 and 39 are reticulated or formed of wire screens 71 and the upper, rear portion of the stacker casing is provided with 100 screened openings 72. These openings are preferably formed in a pair of slide-plates 73 which may be shifted back and forth laterally to afford access to the upper portion of the stacker casing. A hinged door 74 is 105 arranged in the rear wall of the stacker casing below the slide-plates 73 and between a pair of cross angle-bars 75. By opening this hinged door, access may be had to the lower portion of the stacker casing and to the 110 sieves in the lower portion of the threshing machine. The side walls of the stacker casing are also preferably provided adjacent the ends of the sieves 15 with openings closed by slide-plates 76 and the top of the stacker 115 casing in front of the delivery chute section is provided with slides 77 which can be opened to afford access to the interior of the casing at this point.

The delivery chute section may be of any 120 desired construction, but in the preferred form it is provided with an endless conveyer pivoted thereto. This conveyer comprises an open topped trough or chute 78 fixed at its inner ends to a pair of triangular brackets 79. These brackets are pivotally mounted upon a cross-shaft 80 which is journaled in suitable bearings upon the lower, rear

portion of the hood 38. This shaft forms the pivot upon which the conveyer section may be raised and lowered as is desirable in forming the stack. An endless raddle 81 having cross slats 82 extends through the conveyer 78 and over pulleys (not shown) at its outer end and over drive pulleys on the shaft 80. An assisting conveyer is arranged within the hood 38 and below the inclined top wall thereof. This assisting conveyer comprises a pair of chains 84 connected by cross-bars 85 and extending over sprocket wheels 86 on a pair of shafts 87 and 88. The bearings of the upper shaft 87 are fixed and the bearings 89 of the lower shaft are longitudinally adjustable to place the proper tension upon the conveyer chains 84. This assisting conveyer extends in inclined position across and adjacent the inner end of the endless delivering conveyer and the straw is forced up between the conveyers and onto the delivery conveyer, this action being assisted by the short, supplemental conveyer within hood.

25 A transverse shaft 90 extends between the upper corners of the triangular bracket 79 and carries a pair of pulleys 91 thereon. Ropes 92 fixed at one end of the shaft 90, extend over the pulleys 91 and over a windlass 93 fixed to the upper portion of the hood 38 and serve to raise and lower the delivering conveyer section of the stacker. The shaft of the windlass 93 is provided with an operating crank-arm 94 and with a locking ratchet 95 by which it may be held in adjusted position.

40 A shield 96 comprising a top wall and depending side walls 97 is pivoted by a cross-rod 98 to the upper portion of the hood 38 in front of the elbow 61. At its free end, the pivoted shield is provided with a cross-rod 99 which rests upon the side walls of the conveyer trough or chute 78. This shield thus rises and falls with the conveyer section. A fixed, curved shield 100 is arranged within the hood 38 at the rear portion thereof and below the mouth of the elbow 61 and above the short, assisting conveyer. The shields 96 and 100 coöperate to insure the delivery of the chaff projected from the elbow 61 by the blast into the straw. Drive mechanism for the conveyers on the rotatable section of the stacker comprises a short, horizontal shaft 101 (see Figs. 1 and 8) that is journaled in suitable bearings upon a cast metal bracket 102 on the top wall 103 of the stacker at one side of the rotatable stacker section. This shaft is driven by a chain 104 which passes over a sprocket wheel 105 thereon, over a sprocket wheel 106 on the end of the main transverse drive shaft 51 and over a tightener sprocket 107. This tightener sprocket is mounted upon an adjustable bracket 108, so that the proper tension can be placed upon the chain.

The inner end of the shaft 101 is provided with a beveled gear which meshes with the lower portion of a double faced gear ring 110. This gear ring is formed of upper and lower connected sections and is rotatably supported on the cylindrical casting 35 by a row of balls 111 arranged between the sections of the gear ring and between the sections of the casting 35. A short shaft 112 is journaled in a bracket 113 on the flange 36 and carries a gear 114 at its inner end that meshes with the upper set of teeth on the gear ring 110. A sprocket wheel 115 is fixed on the outer end of the shaft 112 and a chain 116 extends over this wheel, over a sprocket wheel 117 on the end of the delivery conveyer shaft 88 and over a tightener sprocket 118. The tightener sprocket is carried on an adjustable bracket 119, and the upper portion of the chain, near the tightener sprocket, engages a sprocket wheel 120 on the outer end of the assisting conveyer shaft 87. This mechanism serves to drive the conveyers in any position of the rotatable delivery section of the stacker.

95 The delivery section of the stacker is swung back and forth by a shaft 121 journaled at the upper portion of the stacker frame. A worm 122 on this shaft engages a worm wheel 123 formed on the cylindrical casting 35. At its outer end (see Figs. 2, 3, 4 and 8) the shaft 121 has a ratchet wheel 124 fixed thereto that is provided with internal, double-faced teeth 125. A pawl actuating arm 126 loosely mounted on the shaft 100 is pivoted to the end of an eccentric rod 127 that engages an eccentric 128, on a short shaft 129. This shaft is mounted in bearings on the bracket 102, and carries a gear 130 fixed to the eccentric 128 and meshing with the teeth of a gear 131 on the shaft 101. A shifter disk 132 is loosely mounted on the shaft 121 adjacent the ratchet wheel 124 and is provided with two segment flanges 133 which are arranged to alternately engage a pair of oppositely acting pawls 134 pivoted on the actuating arm 126. By throwing the shifter disk 132, the pawls 134 may be alternately thrown into and out of operation to rotate the shaft 121 and the delivery section of the stacker in opposite directions. The shifter disk is automatically moved by an arm 135 pivoted to the bracket 102 and connected to the disk by a link 136. The end of this link engages a slot 135a in the arm. A pivoted spring dog 137 on the arm is arranged to engage a roller 138, and holds the arm in one or the other position. The arm is knocked back and forth by a pair of lugs or pins 139 that are adjustably arranged in a series of holes 140 in the flange 37, so that the throw of the rotatable stacker section may be varied as desired. The swing of the delivery stacker section may be arrested if desired, by a 138

short arm 141, carried by a bolt 142 on the pawl actuating arm, and which can be shifted to hold the operating pawl in idle position. A spring 143 on the bolt 142 and a series of interlocking teeth 144 formed on the arms 141 and 126 serve to hold the stop-arm 141 in position.

The joint between the fixed and the rotatable sections of the stacker conduit is made fairly snug by a sheet metal ring 145 fixed to the throat 30 and extending within the casting 31. The bearings of the shafts 44 are connected to the rear portion of the frame 18 by brace rods 146. The lower edge of the partition plate 28 is connected to a transverse angle bar 147.

It is often desirable to separate the chaff and straw. This can be readily accomplished with the present improved stacker, since the horizontal pipe section is swiveled within the vertical pipe section 59. A pair of flanged rings 148 are fixed to the pipe sections 59 and 60 and are connected by clamp bolts 149 extending through ears on one of the rings and having washers 150 engaging the other ring. The pipe section 60 and the elbow 61 are similarly connected. By loosening the wing nuts on the bolts 149, the pipe section 60 and the elbow 61 can be turned to deliver the chaff at any desired point and keep it separate from the straw. The vertical pipe section is connected to the upper portion of the stacker frame by clamping ring bars 153. The ring flange 62 on the end of the elbow 61 is held down on the top of the rotatable hood 38 by turn buttons 151 which are normally held in engagement with the flange by pins 152. These parts can be readily shifted to release the elbow when it is desired to keep the chaff separate from the straw.

It is obvious that the details set forth can be varied without departure from the essentials of the invention and that parts thereof can be employed without adopting it in entirety.

I claim as my invention:

1. In a force feed straw stacker, the combination of a closed unobstructed conduit or pipe, a hopper having a contracted outlet portion arranged in alinement with said conduit and opening into the inner end thereof and in line therewith, and a series of packing devices arranged to move through said hopper and compress the straw into said contracted outlet to thereby force the same through said conduit, substantially as described.

2. In a force feed straw stacker, the combination of a closed conduit or pipe, a hopper having a contracted outlet opening into the inner end of said conduit and in line therewith, and two sets of alternately acting packing devices arranged on opposite sides of and adjacent the inner end of said con-

duit and having a combined reciprocating and rotary motion, said packing devices being arranged to move through said hopper and compress the straw into said contracted outlet to thereby force the same through said closed conduit, substantially as described.

3. In a force feed straw stacker, the combination of an upwardly extending conduit, a hopper having a contracted outlet portion arranged in alinement with said conduit and opening into the lower inlet end thereof, and a series of alternately acting packing devices arranged outside of said hopper and operating through slots therein to compress the straw into said contracted outlet and thereby force the same through said conduit, substantially as described.

4. In a force feed straw stacker, the combination of an upwardly leading, flaring throat, a hopper having a contracted outlet arranged in alinement with said flaring throat and opening into the lower small end thereof, and a series of alternately acting packing devices movable through said hopper toward said contracted outlet and arranged to compress the straw into said contracted outlet and through said flaring throat, substantially as described.

5. In a force feed straw stacker, the combination of a closed conduit comprising a stationary, upwardly leading, expanded throat section, and a shiftable delivering stacker-section leading from the upper large end of said throat, a hopper having a contracted outlet portion arranged in alinement with said throat and opening into the lower small end thereof, and a series of alternately acting packers movable through said hopper and arranged to compress the straw into the contracted outlet thereof to thereby force the same through the stationary throat and the shiftable delivering sections of said conduit.

6. In a force feed straw stacker, the combination of an upwardly leading stationary throat, a delivering conveyer communicating with the upper end of said throat, a hopper having a contracted outlet portion arranged in alinement with said throat and opening into the lower end thereof, and a series of packing devices having a combined reciprocating and rotary motion movable through said hopper and arranged to compress the straw into the contracted outlet thereof to thereby force the same through said throat and onto said conveyer, substantially as described.

7. In a force feed straw stacker, the combination of an upwardly leading, expanded, stationary throat, a rotatable support surrounding the upper end of said throat, an endless conveyer pivoted on said rotatable support, a hopper having a contracted outlet opening into the lower inlet end of said

throat and in line therewith, a series of packing devices movable through said hopper and arranged to compress the straw into the contracted outlet thereof to thereby force the same through said throat and onto said endless conveyer, and mechanism for operating said packing devices and said conveyer, substantially as described.

8. In a straw stacker, the combination with a straw receiving hopper, of a stationary throat leading upwardly therefrom, a rotatable support surrounding the upper end of said throat, an endless delivering conveyer pivoted on said support, a short assisting conveyer arranged adjacent the inner end of said delivering conveyer and a series of packing devices for forcing the straw through said throat and between said conveyers.

9. In a straw stacker, the combination of a stacker casing having separate upper and lower hoppers for respectively receiving straw and chaff, a shiftable, delivering stacker-section, a throat leading upwardly from said upper hopper to said shiftable, delivering stacker-section, a conduit separate from and independent of said throat leading upwardly from said lower hopper directly to said shiftable, delivering stacker-section, a series of packers movable through said hopper for forcing the straw therefrom through said throat, and a fan for forcing the chaff from said lower hopper through said conduit, substantially as described.

10. In a straw stacker, the combination of a stacker-casing having separate upper and lower hoppers for receiving straw and chaff, a closed conduit comprising a throat section leading upwardly from said straw hopper and a rotatable section communicating with the upper end of said throat section, a pipe leading from said chaff hopper and opening into said rotatable conduit section in line with the axis thereof, a series of packers for forcing the straw through the throat and rotatable sections of said conduit, and a fan for forcing the chaff through said pipe.

11. In a straw stacker, the combination of a stacker-casing having separate upper and lower hoppers for receiving straw and chaff, a throat leading upwardly from said straw hopper, a rotatable support surrounding said throat, a hood on said rotatable support, a fan casing communicating with said chaff hopper, a pipe leading from said fan casing and opening into the upper end of said hood, in line with the axis of said rotatable support, a series of packing devices for forcing the straw through said throat, a screw conveyer in said chaff hopper and a fan in said casing for forcing the chaff through said pipe to said hood.

12. In a straw stacker, the combination

of a stacker frame or casing having a straw hopper comprising an upwardly inclined bottom wall and a pair of slotted, curved, inclined side walls, a throat leading upwardly from said hopper, a pair of inclined crank shafts arranged outside of and parallel to the side walls of said hopper, packer arms mounted upon the cranks of said shafts and having teeth adapted to be projected through said slots, links connecting said packer arms to stationary brackets and mechanism for driving said shafts in opposite directions.

13. In a straw stacker, the combination of a stacker frame or casing having an upper hopper and a lower hopper for receiving straw and chaff, a throat leading from said upper straw hopper, a rotatable delivering stacker-section leading from said throat, a pipe leading from said chaff hopper to said rotatable stacker-section, a series of packers for forcing the straw from said upper hopper through said throat, a fan for forcing the chaff through said pipe, the walls of said stacker frame or casing being provided with reticulated portions to relieve the air blast from the thresher.

14. In a force feed straw stacker for threshing machines, the combination with a stacker frame or casing adapted to be mounted upon and inclose the rear end of the threshing machine, a delivery stacker-section rotatably mounted on the upper end of said stacker frame or casing, and mechanical feeding devices for forcing the straw upwardly through said frame or casing to said delivery stacker section, the walls of said stacker frame or casing being provided with reticulated portions to relieve the blast of air from the thresher.

15. In a straw stacker, the combination of an upper hopper for receiving straw, a lower hopper arranged below the same for receiving chaff, a delivering stacker-section leading from said upper hopper, mechanism for forcing the straw from said upper hopper onto said delivering stacker-section, a discharge pipe leading from said lower hopper, and a fan for forcing the chaff through said discharge pipe, said discharge pipe having an adjustable, swinging section adapted to be detachably connected to said delivering stacker-section to convey the chaff thereto, substantially as described.

16. In a force feed straw stacker, the combination with an upwardly extending unobstructed flaring throat, of a hopper having a contracted outlet at its upper portion opening into the lower smaller end of said flaring throat and in line therewith, and a series of packing devices movable upwardly through said hopper for compressing the straw into said outlet and thereby force the same through said throat, substantially as described.

17. In a force feed straw stacker, the combination of an upwardly extending, expanded throat, a shiftable, delivering stacker-section leading from the upper large end of said expanded throat, a hopper having a contracted outlet at its upper portion opening into the lower small end of said throat and in line therewith, and a series of feeding devices movable upwardly through said hopper for forcing the straw through said contracted outlet and said throat onto said delivering stacker-section, substantially as described.
